(57) **CLAIM**

The ornamental design for a high-bay luminaire, as shown and described.

DESCRIPTION

High-bay luminaire

Fig. 1.1 is a top-down perspective view showing of a high-bay luminaire showing our new design;

Fig. 1.2 is a front view showing of a luminaire showing our new design;

Fig. 1.3 is a back view thereof;

Fig. 1.4 is a right side view thereof;

Fig. 1.5 is a left side elevational view thereof;

Fig. 1.6 is a top plan view thereof;

Fig. 1.7 is a bottom plan view thereof.

The broken lines in the reproductions illustrate portions of the high-bay luminaire that form not part of the claimed design.
